UNITED STATES PATENT OFFICE

2,373,562

FREQUENCY MODULATION RECEIVER

Clarence W. Hansell, Port Jefferson, N. Y., assignor to Radio Corporation of America, a corporation of Delaware

Original application June 17, 1941, Serial No. 398,391. Divided and this application September 22, 1942, Serial No. 459,273

5 Claims. (Cl. 250—20)

This application is a division of my application Serial No. 398,391, filed June 17, 1941, Patent No. 2,323,596, dated July 6, 1943. This invention relates to new and improved methods of, and means for, reception of frequency modulated carrier current. In its broader aspects it involves new and improved methods of, and means for, carrying out the fundamental principles of frequency modulation (F. M.) reception which were described in my United States Patent No. 1,813,922. In the 10 said patent I described a means for providing constant energy, or constant electrical charge, per cycle of an intermediate frequency (I. F.) carrier current in a superheterodyne frequency modulation receiver, followed by means for integrating 15 and utilizing the successive energies, or currents, to provide an output current, or increment of output current, proportional to the frequency of the intermediate frequency current. That is, I provided means for producing equal energy, or current, pulses at a rate determined by the frequency of an intermediate frequency carrier current, and utilized these pulses to produce a flow of power, or of current, which varied in proportion to frequency variations of the carrier current.

The novel features which I believe to be characteristic of my invention are set forth with particularity in the appended claims; the invention itself, however, as to both its organization and method of operation will best be understood by reference to the following description taken in connection with the drawing in which I have indicated diagrammatically several circuit organizations whereby my invention may be carried into effect.

In describing my invention reference will be made to the attached drawing wherein—

Figs. 1 and 2 each show a modification of a frequency modulated wave energy demodulator arranged in accordance with my invention.

In the arrangement of Fig. 1 received radio signals (FM signal energy) are supplied from antenna A to circuits in unit 2 comprising radio frequency amplifiers, a source of local oscillations, a first detector and I. F. amplifiers. The radio signals are heterodyned down in unit 2 to an intermediate frequency, amplified, and applied by way of resistances 6 and 8 to respective grids 10 and 12 of a pair of electron discharge tubes 14 and 16 which are provided with regeneration sufficient to produce a condition of unstable equilibrium. The regeneration may be obtained in various ways.

In a preferred embodiment the first grid 18 of tube 14 is coupled by series-connected resistance 55

20 and condenser 22 to the anode 24 of tube 16. The third grid 25 of tube 16 is coupled by series-connected resistance 26 and condenser 28 to the anode 30 of tube 14. These couplings provide regeneration to produce an unstable condition so that over the operating frequency range, one tube or the other carries a relatively large anode current, while the opposite tube carries zero, or very low, anode current. The transfer of current from one tube to the other takes place twice per cycle of the intermediate frequency input current, and is accomplished in a time period which is short compared with the time of one cycle of the intermediate frequency current.

The two tubes have their anodes 24 and 30 connected in push-pull relation by the primary winding 40 of a transformer 42. The secondary winding 44 of the transformer is connected between the anodes 46 and 48 of a double diode 50. The tubes 14 and 16 are coupled by the transformer 42 to the rectifier 50 which, in turn, supplies audio frequency current through a low pass filter 52 to an audio amplifier 54 and loudspeaker 56.

In operation, the intermediate frequency current controls the frequency rate at which the two tubes, with their circuits, throw the current balance from one tube to the other, but the regenerative feedback determines the quickness of the transition. Therefore, the wave form of current pulses, and the magnitude of electrical charge per pulse delivered to the rectifier 50, are substantially independent of the pulse frequency rate. Consequently, the mean direct current passed through the rectifier 50 and low pass filter 52 to the load 54 and 56 is substantially proportional to the pulse rate, provided the load impedance is not too high in comparison with the effective impedance of the source of current for the load.

With this combination, when a frequency modulated radio carrier is being received, there is a corresponding modulation of the intermediate frequency and of the pulse rate. Hence, the rectified current, after going through the low pass filter 52, varies in magnitude substantially in proportion to the frequency, and has variations corresponding to the modulation of received currents. In the arrangement of Fig. 1, I have shown tubes 14 and 16 each having three grids placed successively in the electron stream between cathode and anode. In each tube one grid (grid 10 in tube 14 and grid 12 in tube 16) receives the intermediate frequency control potential, another acts as a screen (grid 10' in tube 14 and grid 12' in tube 16) between tube input and output cir-

cuits, and the third (grid 18 of tube 14 and grid 25 of tube 16) is utilized for feedback potentials to provide the desired instability of current balance between the two tubes. The two tubes and their circuits are closely related to the tripping circuit invented by my associate, J. L. Finch, as, for example, disclosed in United States Patent No. 1,844,950, dated February 16, 1932, which has found wide application in communications systems.

Since, as pointed out above, the magnitude of the electrical charge per pulse delivered to the rectifier 50 is substantially independent of the pulse frequency rate, the arrangement of Fig. 1 automatically performs the functions of an amplitude limiter and frequency modulation detector, and differs from the circuit of the aforesaid Finch patent in this important respect. The circuit of Fig. 1 performs the functions with simpler and lower cost equipment, which produces less distortion when correctly proportioned.

The system of Fig. 1 may be modified as illustrated in Fig. 2. In Fig. 2 the antenna A feeds the FM signals to the heterodyne detector and intermediate frequency amplifying means 3. In the latter there is reduced the frequency of the received modulated wave, while increasing the percentage modulation thereof. Network 3 feeds the I. F. energy to transformer 5, and, thence, by way of resistances 6 and 8 to the control grids 18 and 25 of tubes 14 and 16 which in this modification are triodes. These grids 18 and 25 are cross-connected by resistances 23 and 21, respectively, to the anodes 24 and 30, respectively, to form a tripping circuit similar to that of Fig. 1. The tubes 14 and 16, as explained in detail in connection with Fig. 1, alternately pass current. The duration of the impulses depends on the constants of the tube circuits, and is substantially independent of the amplitude of the input. The frequency of reversal (twice per cycle of applied intermediate frequency current) depends on the frequency of the input. The alternating current output is fed to transformer 42, and rectified as in Fig. 1.

I have illustrated my novel frequency modulation detector circuits as applied to radio receivers, but it should be apparent that they are also applicable to any kind of frequency modulation communication or telemetering system, including electrical communication over wire circuits, through wave guides, and signalling by vibrational waves through gases, solids or liquids, such as submarine signalling. They may be used advantageously in receiving sub-carrier frequency modulated signals in multiplex systems, and in facsimile communications systems such, for example, as disclosed in C. W. Hansell Patent No. 1,819,508, dated August 18, 1931; C. W. Hansell Patent No. 2,103,847, dated December 28, 1937; R. H. Ranger Patent No. 1,830,242, dated November 3, 1931; J. N. Whitaker application Ser. No. 311,495, filed December 29, 1939; H. O. Peterson application Ser. No. 384,628, filed March 22, 1941; H. Tunick application Ser. No. 369,800, filed December 12, 1940; H. O. Peterson application Ser. No. 341,285, filed June 19, 1940; H. H. Beverage Patent No. 2,025,190, dated December 24, 1935.

The invention, and the detail arrangements shown, provide for substantial suppression of amplitude modulations, or amplitude limiting, as well as for demodulation of frequency modulated waves with simpler and less expensive equipment than heretofore used.

While I have indicated and described several

systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In means for demodulating frequency modulated wave energy, a pair of electron discharge tubes each having at least an anode, a cathode and a control electrode, circuits cross-connecting the anodes and control electrodes of said tubes to thereby connect the same in a regenerative circuit whereby pulses of current of constant amplitude are generated, means for impressing frequency modulated wave energy in push-pull relation on the control electrodes of said tubes whereby the rate of said pulse generation is controlled in accordance with the wave energy frequency, a rectifier coupled to the anodes of said tubes for rectifying said pulses, and a low pass filter coupled to said rectifier to pass the modulation components of the rectified pulses.
2. In means for demodulating modulated wave energy, a pair of electron discharge tubes, each including an anode, a cathode and a plurality of control electrodes, means cross-connecting each anode and a first control electrode of the opposite tube thereby providing cross-regeneration between the tubes, means for impressing negative potentials on said control electrodes relative to said cathodes, means for impressing modulated wave energy in phase opposition on second control electrodes of said tubes, whereby impulses of current are produced on the anodes, and a rectifier coupled to the anode electrodes to rectify said current impulses.
3. In a receiver of angular velocity-modulated carried wave energy, an amplitude limiter stage comprising a pair of tubes having a common wave energy input circuit, each tube including at least a cathode, anode and control electrode, a common output circuit connected to the anodes of said tubes, a regenerative feedback path connected between the anode of each tube and an electron control element of the opposite tube whereby there are produced pulses of current of a controllable rate and of substantially constant amplitude, means for connecting said control electrodes to said common input circuit in push-pull relation whereby the rate of pulse production is controlled in accordance with the frequency of received modulated wave energy, and means coupled to said common output circuit for utilizing the controlled pulses.
4. In a receiver of angular velocity-modulated carried wave energy, an amplitude limiter stage comprising a pair of tubes having a common wave energy input circuit, each tube including at least a cathode, anode and control electrode, a common output circuit connected to the anodes of said tubes, a regenerative feedback path connected between the anode of each tube and an electron control element of the opposite tube whereby there are produced pulses of current of a controllable rate and of substantially constant amplitude, means for connecting said control electrodes to said common input circuit in push-pull relation whereby the rate of pulse production is controlled in accordance with the frequency of received modulated wave energy, and means coupled to said common output circuit for utilizing the controlled pulses and said electron control

elements consisting of auxiliary control electrodes provided in said two tubes.

5. In a receiver of angular velocity-modulated carried wave energy, an amplitude limiter stage comprising a pair of tubes having a common wave energy input circuit, each tube including at least a cathode, anode and control electrode, a common output circuit connected to the anodes of said tubes, a regenerative feedback path connected between the anode of each tube and an 10 electron control element of the opposite tube whereby there are produced pulses of current of

a controllable rate and of substantially constant amplitude, means for connecting said control electrodes to said common input circuit in push-pull relation whereby the rate of pulse production is controlled in accordance with the frequency of received modulated wave energy, and means coupled to said common output circuit for utilizing the controlled pulses, said electron control elements being said control electrodes of the two tubes, and a rectifier network functioning as said utilizing means.
